US0D1093913S

(12) United States Design Patent (10) Patent No.: US D1,093,913 S
(45) Date of Patent: * Sep. 23, 2025

(54) SURFACE PATTERN FOR SEATS

(71) Applicant: KETER HOME AND GARDEN PRODUCTS LTD., Herzliya (IL)

(72) Inventor: Hanna Spaander, Ede (NL)

() Term: 15 Years

(21) Appl. No.: 35/523,793

(22) Filed: Dec. 9, 2024

(80) Hague Agreement Data

Int. Filing Date: Dec. 9, 2024

Int. Reg. No.: DM/243558

Int. Reg. Date: Dec. 9, 2024

Int. Reg. Pub. Date: Jan. 31, 2025

(30) Foreign Application Priority Data

Jun. 10, 2024 (IL) 72678

(51) LOC (15) Cl. 05-03

(52) U.S. Cl.

USPC D5/47

(57) CLAIM

The ornamental design for a surface pattern for seats as shown and described.

DESCRIPTION

1. Surface pattern for seats

1.1 : Perspective

1.2 : Front

1.3 : Reference view

1.4 : Left

1.5 : Right

1.6 : Top

1.7 : Bottom

1.8 : Back

1.9 : Reference view

The parts colored in blurry white separated by dashed lines in reference views 1.3 and 1.9 show the pattern as part of the seat and are shown for illustrate portions of the seat, which form no part of the claimed design; the dashed lines surrounding the dark grey areas represent the boundaries of the claimed design and form no part thereof.

1 Claim, 9 Drawing Sheets
